Primary Examiner — Patricia A Palasik*(74) Attorney, Agent, or Firm* — Jason P. Mueller; FisherBroyles, LLP(57) **CLAIM**

The ornamental design for a vibratory screening machine, as shown and described.

DESCRIPTION

FIG. 1 is a top perspective view of a vibratory screening machine;

FIG. 2 is a bottom perspective view thereof;

FIG. 3 is a right side view thereof;

FIG. 4 is a left view thereof;

FIG. 5 is a front view thereof;

FIG. 6 is a back view thereof;

FIG. 7 is a top view thereof; and,

FIG. 8 is a bottom view thereof.
